WILLIAM T. AYER, OF DOVER, NEW JERSEY, ASSIGNOR TO MCKIERNAN-TERRY DRILL COMPANY, OF DOVER, NEW JERSEY, A CORPORATION OF NEW JERSEY.

SPRING-MUZZLE FOR ROCK-DRILLING ENGINES.

1,170,501.

Specification of Letters Patent.

Patented Feb. 8, 1916.

Application filed May 22, 1915. Serial No. 29,938.

To all whom it may concern:

Be it known that I, WILLIAM T. AYER, a citizen of the United States of America, and a resident of Dover, county of Morris, 5 and State of New Jersey, have invented certain new and useful Improvements in Spring-Muzzles for Rock-Drilling Engines, of which the following is a specification, reference being had to the accompanying 10 drawings, forming a part thereof.

My invention relates to power drills and has special reference to rock drills of the hammer type.

One object of my invention is to provide 15 a simple and improved spring muzzle for withdrawing a drill from the hole, that shall be adapted to act as a substantially rigid structure under certain conditions.

Other objects and advantages of my invention will be set forth hereinafter, and in order that my invention may be thoroughly understood, I will proceed to describe the same in the following specification and then point out the novel features 25 thereof in appended claims.

Referring to the drawings: Figure 1 is an elevation looking at one side of the spring muzzle, of a drilling engine embodying my invention. A partially sectional elevation 30 taken at right angles to Fig. 1 and drawn to a larger scale, is shown in Fig. 2. Fig. 3 is a sectional plan view on the line 3—3 of Fig. 2, and Fig. 4 is a perspective view of one of the parts of the spring muzzle.

A drilling engine is shown at 10 in the drawings and has a cylinder extension 11 and a socket 12 in which the shank of a drill steel 13 is supported. Extending laterally in opposite directions from the cylinder extension 11 are a pair of lugs 14 on which the spring muzzle is pivotally mounted.

The spring muzzle comprises a pair of clevises 16 and 17 which are laterally perforated at 19 to fit onto the lugs 14 and have 45 longitudinal holes 20 at their outer ends through which the substantially parallel ends 21 of a resilient yoke 22 extend. As clearly shown in Fig. 4, this yoke has a loop 23 in a transverse plane relative to the 50 remainder of the yoke, and a pair of inclined sections 24 which connect the parallel ends 21 with the ends of the loop 23. The arrangement of parts is such that the loop is adapted to fit freely onto the drill steel 13 as shown in Figs. 1, 2, and 3 and pre-

vents it from falling out of the socket 12 by engaging an enlargement or collar 25 with which the drill steel is provided. After the ends 21 of the yoke have been thrust through the holes 20, helical springs 60 27 are mounted on them within the clevises, after which nuts or heads 26 are affixed to their extremities. The arrangement of parts is such that the yoke which is itself formed of resilient material such as spring 65 steel, is resiliently connected to the clevises 16 and 17 above described. The clevises are held in substantially parallel relation since they are mounted on the parallel ends 70 21 of the yoke, but the yoke is sufficiently resilient to permit the spreading of the clevises apart while the muzzle is being mounted on the cylinder extension of the engine. In the operation of the muzzle there is no tendency for the clevises to separate 75 and the spring tension of the yoke is sufficient to hold them in position on the lugs 14. While the lugs are located on opposite sides of the cylinder extension they are not in the central plane of the drill but are offset 80 as clearly shown in Fig. 1. This is for the purpose of permitting the helical springs 75 27 to spring past the center of the extension 11, which is cylindrical in form, and to lie close to its sides so that they tend to hold the 85 yoke in position as clearly shown in Fig. 1, the closed end of the loop 23 of the yoke being on the opposite side of the central plane of the drill, from the plane of the lugs 14.

From the foregoing description it is apparent that the spring muzzle may be swung upon the lugs 14 as an axis either out of the way, to permit the ready insertion or removal of a drill steel from the socket 12, or into position to grip the drill steel loosely and prevent its falling out of the socket 12 when the drill steel is being removed from a hole.

When holes are drilled to a considerable 100 depth it is comparatively difficult to remove the drill steel from the hole and it is frequently found desirable to continue to operate the drilling engine while an outward pull is exerted upon it. The drill steel then 105 occupies the position shown in Fig. 1 and sticking of the drill steel in the hole causes the spring 27 to close up to a greater or less extent. Then the continued operation of the piston or hammer jars the engine and 110

the drill steel thereby assisting in loosening it and permitting it to be withdrawn easily.

Structural variations may be effected within the spirit and scope of my invention and I intend that only such limitations be imposed as are indicated in appended claims.

What I claim is:

1. A spring muzzle for drilling engines comprising a resilient yoke, a pair of side members adapted to be pivotally mounted on the engine and a yielding connection between the yoke and the side members.

2. A spring muzzle for drilling engines comprising a resilient yoke, a pair of clevises into which the ends of the yoke extend, and means for yieldingly holding the ends of the yoke in the clevises, said clevises being adapted to be pivotally mounted on the engine.

3. A spring muzzle for drilling engines comprising a resilient yoke having a loop in a lateral plane and a pair of substantially parallel spaced end members with heads, clevises into which the end members extend, helical springs interposed between the heads of the end members and the opposite ends of the clevises, said clevises being adapted to be pivotally mounted on oppositely extending lugs on the engine.

4. In combination with a drilling engine having a cylindrical member provided with oppositely extending lugs and a socket adapted to receive a drill steel, of a spring muzzle comprising a resilient yoke pivotally mounted at its ends on the lugs and having a loop adapted to engage the drill steel, said

lugs being offset from the central plane of the drill socket whereby the yoke is adapted to be sprung past the center of the cylindrical member and resiliently hold the loop 40 against the drill steel.

5. In combination with a drilling engine having a cylindrical member provided with a socket adapted to receive a drill steel and oppositely extending lugs in a plane offset 45 relative to the central plane of the socket, of a spring muzzle comprising a resilient yoke having a loop in a lateral plane and a pair of substantially parallel spaced end members with heads, clevises into which the 50 end members extend, helical springs interposed between the heads of the end members and the opposite ends of the clevises, said clevises being adapted to be pivotally mounted on the oppositely extending lugs 55 of the engine and said muzzle being adapted to be sprung past the center of the cylindrical member to resiliently hold the loop against a drill steel.

6. In combination with a drilling engine 60 having a cylindrical member provided with oppositely extending lugs in a plane offset relative to the central plane of the member, of a spring muzzle comprising a yoke pivoted near its ends upon the lugs and adapted 65 to hold a drill steel, the arms of said yoke being adapted to spring past the center of the cylindrical member and thereby press the muzzle against the drill steel.

In witness whereof I have hereunto set 70 my hand this 20th day of May, 1915.

WM. T. AYER.
